UNITED STATES PATENT OFFICE.

HARRY S. VINCENT, OF RIDGEWOOD, NEW JERSEY, ASSIGNEE TO FRANKLIN RAILWAY SUPPLY COMPANY, A CORPORATION OF DELAWARE.

LOCOMOTIVE.

Application filed April 26, 1924. Serial No. 709,074.

To all whom it may concern:

Be it known that I, HARRY S. VINCENT, a citizen of the United States, residing at Ridgewood, in the county of Bergen and State of New Jersey, have invented certain new and useful Improvements in Locomotives, of which the following is a specification.

This invention relates to locomotives and its nature, objects and advantages will be best understood from the following:

One of the principal objects of this invention is to provide a locomotive which will carry increased tonnage over the division at speed (say at 30 miles per hour in freight service). This cannot be done by glorifying, so to speak, the present locomotive for the reason that the existing bridges impose a definite limitation of the weight of the locomotive.

To meet this condition I propose to overpower the locomotive either by stepping up the boiler pressure or increasing the size of cylinders over what is standard for the particular class of locomotive, or both. The locomotive, therefore, has an appreciably lower factor of adhesion than normal for the particular class, in which connection locomotive design has become so crystallized that the factor of adhesion for any given type of locomotive is well determined and defined and varies but very slightly.

Such a locomotive because of its ability to develop a tractive effort in excess of the limits of weight adhesion is slippery and could not be started under the loads which it is contemplated the locomotive shall draw.

To meet this condition, I propose to so operate the locomotive in starting that the tractive effort exerted is reduced to the point where tractive effort bears a practicable relation to adhesive weight, i. e., reduced to the point where the locomotive is not a slippery one.

However, the locomotive then will be able to start only the load which an engine having a normal factor of adhesion could start, and would not be able to start the increased tonnage which it is expected to carry over the division at speed.

To meet this condition I apply an auxiliary motor to normally idle wheels such as the tender or trailer truck wheels which, though smaller than the drivers, have a very

high factor of adhesion and will therefore 55 materially supplement the tractive effort exerted by the locomotive in starting, producing a total draw bar pull sufficient to start the increased tonnage which the locomotive itself will later carry at speed. 60

How the foregoing, together with such other objects and advantages as may herein-after appear or are incident to my invention, are obtained, is illustrated in the accompanying drawings in diagrammatic character. 65

The figure is a diagrammatic side elevation of a locomotive embodying my improvements.

As above pointed out, in carrying out my 70 invention, I intentionally design the locomotive to have a low factor of adhesion, materially lower than standard for the particular class of locomotive. I prefer to bring this about by increasing the boiler pressure 75 materially above what would be standard for the given type of locomotive, for reasons which will appear hereinafter. The locomotive, therefore, will exert greater tractive effort in relation to adhesive weight 80 than is normal for the particular type of locomotive, and will be capable of sustaining a greater train in motion at speed, and will be susceptible of being operated at shorter cut-offs than would be standard for 85 the particular class of locomotive, as a result of which it is economical in steam consumption at speed.

To overcome the slipperiness in starting, I propose to reduce the tractive effort which 90 the locomotive is capable of exerting in starting, to an extent such that the tractive effort bears a practicable relation to the adhesive weight of the locomotive by providing the locomotive with a limited maximum 95 cut-off. Ordinarily a locomotive has a 90% maximum cut-off and I prefer to operate in the neighborhood of a 50% or 60% maximum cut-off. In any event, the cut-off 100 should be limited to a maximum such that the tractive effort which the locomotive is capable of developing in starting will not exceed the limit of adhesion.

In the drawing, I have diagrammatically 105 illustrated a reverse lever and power reverse gear for operating the usual valve motion (not shown) of the locomotive, the reverse lever quadrant having a stop 7 which limits

the forward movement of the reverse lever and thus fixes the percentage of maximum cut-off.

In order to get steam into the cylinders of the main engines to initiate starting, any suitable arrangement, such for example as that shown in the Kiesel Patent #1,307,821 may be employed. In accordance with this patent, a port admits steam to the cylinders in starting which port becomes ineffective as soon as the wheels have started to turn, the subsequent admission of steam being controlled by the valves functioning at the limited maximum cut-off. Thus the tractive effort which the locomotive develops in starting is reduced almost instantaneously after the opening of the throttle and the entry of steam into the main cylinders, and hence the locomotive is not slippery and has, so to speak, a normal factor of adhesion.

In this instance, I have shown the trailer wheels equipped with the auxiliary motor or booster device 8, such motor serving to drive such normally idle wheels to aid the main locomotive in starting the train and maintaining it in motion at slow speed. In addition to the functions already pointed out, there is a decidedly advantageous relation between the limited maximum cut-off and the booster for the reason that with such a limited maximum cut-off, the engineer is not required to operate with the throttle choked so as to avoid slipping of the main drivers. The booster motor is operated with steam from the boiler and hence, when the engineman chokes his throttle to prevent slippage of the main drivers, he cuts down the steam supplied to the booster and it does not develop the full power which it is capable of developing. With the throttle wide open, as is now practical by reason of my invention, the booster is always ensured of full steam supply and therefore will develop its maximum power. It is in connection with this that I prefer to decrease the factor of adhesion by stepping up the boiler pressure. For obvious reasons the space available for the application of a booster either to a tender truck or a trailer truck is very small, and hence the size of the booster cylinders is necessarily small. By stepping up the boiler pressure, I increase the power which the small cylinders can develop, and by operating the main engines in starting at a limited maximum cut-off, the booster, as above pointed out is always ensured of being supplied with full steam.

The booster also makes use of the excess boiler capacity available at starting and slow speeds.

Thus all parts cooperate toward the desired results, which include the starting of a much heavier train and the carrying of such a train over the division at speed.

Another advantage incident to my arrangement is that it is practically impossible to drain the boiler of steam. Thus for example even though the locomotive is drawing a train over a long heavy grade at slow speeds, the main engine will be working expansively and such engine and the booster engine together cannot draw steam in excess of the boiler capacity.

I claim:

1. A locomotive having cylinders larger than normal for the adhesive weight of the locomotive, means whereby the steam for propelling the locomotive at starting and at low speeds is permitted to enter the cylinders only in such quantities as to develop normal tractive effort and an auxiliary motor for driving normally idle weight supporting wheels during this period.

2. In combination, a locomotive having a factor of adhesion substantially less than normal, normally idle weight supporting wheels, an auxiliary motor for driving the idle wheels for starting and at low speeds, means for preventing more than normal tractive effort being developed by the locomotive at starting, and at low speeds, but which permits at higher speeds the use of steam more expansively than with a locomotive having a normal factor of adhesion.

3. In combination, a locomotive having a factor of adhesion such that the locomotive, for the particular class, is potentially materially slippery; said locomotive having a cut-off limited to reduce the tractive effort in starting in an amount such that the locomotive in starting is practically normal as to slippage, normally idle wheels having a relatively high factor of adhesion, and an auxiliary engine for driving such idle wheels in starting and at low speeds.

4. In combination, a locomotive having a boiler adapted to develop a normal pressure sufficiently high to develop a tractive effort which will slip the drivers in starting, means for limiting the cut-off to reduce the tractive effort in starting to provide a practicable relation between tractive effort and adhesive weight, normally idle wheels having a high factor of adhesion, an auxiliary motor for driving said wheels.

5. In combination, a locomotive having a boiler adapted to develop a normal pressure sufficiently high to develop a tractive effort which will slip the drivers in starting, means for limiting the cut-off to reduce the tractive effort in starting to provide a practicable relation between tractive effort and adhesive weight, normally idle wheels having a high factor of adhesion, an auxiliary motor for driving said wheels supplied with steam from the boiler.

6. A locomotive having a factor of adhesion substantially less than normal for

the particular class of locomotive, means whereby the tractive effort in starting is automatically held within a figure providing a practicable relation between tractive effort and adhesive weight, normally idle wheels having a high factor of adhesion, and an auxiliary motor for driving said idle wheels in starting.

7. A locomotive having a factor of adhesion substantially less than normal for the particular class of locomotive, means whereby the tractive effort in starting may be held within a figure providing a practicable relation between tractive effort and adhesive weight, normally idle wheels having a high factor of adhesion, and an auxil-

iary motor for driving said idle wheels in starting.

8. A locomotive having a factor of adhesion substantially less than normal for the particular class of locomotive, normally idle wheels having a high factor of adhesion, an auxiliary motor for driving said idle wheels in starting, and means not affecting said motor for reducing the tractive effort of the locomotive in starting in an amount to produce a practicable relation between tractive effort and adhesive weight.

In testimony whereof, I have hereunto signed my name.

HARRY S. VINCENT.
